UNITED STATES PATENT OFFICE.

KENNETH B. HOWELL, OF MAPLEWOOD, NEW JERSEY, ASSIGNOR TO THE BARRETT COMPANY, A CORPORATION OF NEW JERSEY.

CONTINUOUS PULP BEATER.

Application filed August 20, 1923. Serial No. 658,206.

To all whom it may concern:

Be it known that KENNETH B. HOWELL, a citizen of the United States, residing at Maplewood, in the county of Essex and State of New Jersey, has invented certain new and useful Improvements in Continuous Pulp Beaters, of which the following is a specification.

This invention relates to a pulp beater. It relates more particularly to a pulp beater in which the pulp making stock may be continuously fed and the beaten pulp is automatically withdrawn or runs off when it has been beaten to the proper extent. In devices of this character the beaters were formerly operated upon a batch of fibrous material or paper making pulp until the same had been beaten to the proper extent and then the beaten pulp was withdrawn and a new batch was beaten. Devices have also been used in which portions of the pulp have been thrown off by means of the centrifugal force of the beater or the knives carried thereby, but in such cases it sometimes happens that portions of the stock that have been beaten to an insufficient extent were also thrown off and had to be separated from the more finely divided material or produce objectionable results in the final paper. By the present invention the paper making stock can be introduced all at one time or the same may be gradually introduced and the beaten pulp will be drawn off when it has been beaten to the desired extent. The device is especially applicable to beating old papers or other weak fibrous material, although it is not restricted to this sort of material as it is also applicable to rag stock or wood stock or the like, the same requiring a longer period of operation for the proper amount of beating or disintegration of the fibrous material to take place.

The invention will be understood from the description in connection with the drawings, in which—

Fig. 1 is a plan view of the device partly broken away;

Fig. 2 is a section along the line *a—a* of Fig. 1; and

Fig. 3 is a plan view showing one of the details.

In the drawings, reference character 1 indicates the usual beater tub in which the beater roll 2 is located under the hood 3

being driven by the shaft 4 and pulley 5 from any convenient source. The pulp circulates in the usual manner as indicated by the arrows when the beater roll 2 is in operation.

Immediately below the beater roll 2 is located a perforated plate 7 having holes 8 therein, these holes flaring outwardly in a downward direction. Instead of having a flat plate 7 with perforations 8 therein, a reticulated member curved or otherwise suitably shaped or the equivalent may be used with somewhat satisfactory results. The plate 7 is mounted so that a container or receptacle 9 will be therebeneath and an exit trough 10 leads from the side of the container 9 through the wall of the tub to the outside.

The operation is as follows:

The pulp making stock together with water will be introduced into the tub 1 in the usual manner and the beater roll 2 will be set in operation. The current of water and stock will be set up by the beater roll 2 in the direction of the arrows as is the usual case and the stock will at times be drawn between the beater roll 2 and the perforated plate 8 and be dragged thereover thus undergoing disintegration or separation into smaller particles. A certain percentage of the smaller particles will, as the same pass over the perforations 8 of the plate 7, fall through these perforations into receptacle 9 and then be drawn off through the trough 10. The particles that are too coarse for passing through the perforations 8 will be circulated again and undergo further disintegration until the same will be rendered small enough to pass through the perforations. The perforations 8 are made of such a size as not to permit passage therethrough of particles larger than are desired for the paper making and the same are flared outwardly at the bottom to avoid clogging or plugging of the perforations 8 with the fibrous material.

I claim:

1. In a pulp beater having a beater roll, a horizontally disposed reticulated member located below the beater roll and adapted to permit the passage of beaten pulp therethrough.

2. In a pulp beater having a beater roll, a horizontally disposed perforated plate

located in proximity to the beater roll whereby said roll will draw pulp over said plate.

3. In a pulp beater having a beater roll, a perforated plate located in proximity to the beater roll whereby said roll will draw pulp over said plate, the perforation in said plate flaring outwardly in a downward direction.
10. 4. In a pulp beater having a beater roll, a horizontally disposed reticulated member located below the beater roll and adapted

to permit the passage of beaten pulp therethrough and a receptacle below said member.

5. In a pulp beater having a beater roll, a horizontally disposed reticulated member located below the beater roll and adapted to permit the passage of beaten pulp therethrough and means for continuously with- 20 drawing the beaten pulp.

In testimony whereof I affix my signature.

KENNETH B. HOWELL.
